UNITED STATES PATENT OFFICE.

JAMES P. TOLMAN, OF WEST NEWTON, MASSACHUSETTS.

MACHINE FOR MAKING CORDAGE, WEBBING, &c.

SPECIFICATION forming part of Letters Patent No. 276,201, dated April 24, 1883.

Application filed November 10, 1882. (No model.)

To all whom it may concern:

Be it known that I, JAMES P. TOLMAN, a citizen of the United States, residing at West Newton, in the county of Middlesex and State of Massachusetts, have invented certain new and useful Improvements in Machines for Making Cordage, Webbing, &c., of which the following is a full, clear, and exact description, reference being had to the accompanying drawings, making part of this specification, in which—

Figure 1 is a plan of my improved machine, with a portion of the toothed guide-ring and one of the carrier-gears removed, the travelers in their various positions being indicated by disks and sections of their feet. Fig. 2 is a vertical section through the center of the same. Fig. 3 is a plan of a portion of the top of the machine with the parts in a position different from that shown in Fig. 1. Fig. 4 is a plan of the revolving platform of the machine, with two of the switch-levers removed. Fig. 5 is a vertical section of a portion of the revolving platform, with one pair of the switch-levers shown in elevation. Fig. 6 is an elevation of the base or lower portion of one of the travelers. Fig. 7 is a plan of the bottom of a traveler-base.

My invention relates to that class of machines in which the strands forming the cord or webbing are to be united by an interlocking twist, and in which the travelers carrying the strands have an intermittent motion, being at times held in position by a stationary toothed guide-ring or traveler-holding plate, and at other times removed by carrier-gears, with which they revolve, to new positions in such guide-ring. The machines now in use for making cordage in this manner are such as are described in Letters Patent of the United States No. 56,485, granted to James A. Bazin July 17, 1866, and No. 232,920, granted to Chas. E. Barnes October 5, 1880. In both of these machines the traveler-selectors are operated by a complicated mechanism actuated by a cam, which in one of these machines moves a series of sliding plates and in the other a set of pivoted jaws, the object in both cases being to direct the projecting feet of the travelers into their proper places in a main revolving

table or platform. The number of moving parts in these machines greatly increases the cost of building and running them, and the cams wear out very rapidly, requiring frequent repairs and renewals. The lost motion and backlash of the gears also make it very difficult to properly time the machines, and make special devices necessary to operate them in a reverse direction, as is needful when picking out bad work or using yarns with an opposite twist to that usually employed.

The object of my invention is to simplify the construction of the mechanism for selecting the travelers in this class of machines in such a manner as to greatly reduce the cost of their construction, the number of their moving parts, and the rapidity of their deterioration by wear, and to make it possible to revolve the machine at will in either direction without special preparation or any adjustment of the mechanism.

To this end my invention consists in the combination, with the usual revolving platform having one or more circular recesses or guide-paths cut into or formed upon the same, of one or more independent switch levers or points adapted to be operated in one direction by the travelers, and in the opposite direction by a spring or springs, for the purpose of automatically guiding the travelers alternately into and out of the recess or recesses in the revolving platform; and my invention also consists in certain details of construction, as hereinafter set forth and specifically claimed.

In the said drawings, A represents the main revolving platform or table of the machine; E, the circular recesses or guide-paths cut into or formed upon the same, and B C the movable switch levers or points which control the entrances to the recesses E, each lever being pivoted to the platform by means of a stud, e, projecting from its under side and fitting into a hole, d, Figs. 4 and 5.

m n are lugs or stops which serve to limit the range of motion of the switch-levers B C, and b c are springs which are coiled around the studs e, and tend to keep the switch-levers in the position seen in Fig. 4, with their outer ends against the lugs m.

A small portion, a, of the platform A is made removable, to allow of the insertion and re-

moval of the travelers, and is held in place by means of a screw.

F is the guide-ring or traveler-holding plate, which is held stationary at a suitable distance above the platform A by the uprights h of the main frame H of the machine. This guide-ring F is provided on its inner periphery with teeth, of which certain ones at regular intervals, f, are suitably cut away, as seen in Fig. 1, for the purpose of holding the cylindrical necks of the travelers D' D² D³ D⁴ D⁵. In Fig. 1 a portion of the guide-ring is represented as cut away for the purpose of showing the action of the switch-levers beneath.

15 G G are the carrier-gears, (one for each recess E,) arranged in the same plane with the guide-ring F, and provided with studs having their bearings in the platform A, as seen in Fig. 2, by which means the gears are maintained in position above and concentric with the recesses E. These carrier-gears G are rotated by their teeth engaging with the teeth of the guide-ring F as the platform A is revolved, and at suitable intervals the spaces between the teeth of the gears G are properly shaped, as seen at g, for receiving the necks of the travelers.

The operation of the machine is as follows: As the platform A revolves in the direction indicated by the arrow 10, Fig. 1, the carrier-gears G are by the engagement of their teeth with the teeth of the stationary guide-ring F revolved in the direction indicated by the arrows 12, causing the travelers D² and D³, Fig. 1, to be carried thereby around the recesses E. The travelers D³, being in the positions indicated in Fig. 1, hold the switch-levers B in the position seen, thus directing the travelers D' out of the recesses E, around which they have just traveled, into positions in the cut-away teeth f of the guide-ring F, where they are held until the next recess E in the revolving platform A is brought opposite thereto. As the platform continues to revolve, it will pass by the travelers D' in the cut-away teeth f of the ring F, the feet of these travelers bearing against a shoulder at the outer periphery of the platform, and the switch-levers B being carried past the travelers D', so that they will clear the same, and as the travelers D³ will have at the same time been advanced by the rotation of the carrier-gears, the switch-levers B will have been released and returned by their springs b to their normal positions against the lugs m. As the platform still continues to revolve, the feet of the travelers D⁴, which are held in the cut-away teeth of the stationary guide-ring F, will push the switch-levers C aside, allowing them to pass, and the switch-levers B, being at that time in their normal positions against the stops m, will guide the travelers D⁴ into the recesses E, as seen in Fig. 3. When the travelers D⁴ have advanced to the positions represented as 65 occupied by the travelers D³, Fig. 1, the travelers D² will have advanced to the positions

represented as occupied by the travelers D', Fig. 1, and will then be guided out of the recesses E by the switch-levers B into the teeth f of the ring F which are at that moment opposite thereto. At the time that the switch-levers C are being pushed against the lugs n by passing in contact with the travelers D⁴ their curved projecting portions 13 will be removed out of the paths of the travelers D², and when the travelers D⁴ have entered the recesses E and cleared the switch-levers C, the latter will be returned by their springs c to their normal positions against the stops m and allow the passage of the travelers D² out of the recesses E.

It will be seen that when the platform A is revolving in the direction indicated by the arrow 10 the levers B will guide the travelers alternately into and out of the recesses E, the switch-levers C having no work to perform, being merely moved out of the way by contact with the travelers to allow of the free passage of the latter. When, however, the platform A is revolved in the direction opposite to that indicated by the arrow 10, the operation is reversed, the switch-levers C then acting in the same manner as the levers B, above described, and serving to guide the travelers alternately into and out of the recesses E, while the levers B have then no work to perform, being merely moved out of the way by contact with the travelers as they are carried past them, and it will thus be seen that the mechanism can be revolved at will in either direction without special preparation or any adjustment whatever, whereby much delay and inconvenience are avoided and the machine rendered much more valuable.

The platform A is furnished with a sleeve, S, Fig. 2, which revolves around a main spindle, k, rising from the frame H, this spindle k being preferably made hollow, to permit the passage of a core or center for the cord, if such should be required.

To the sleeve S is secured, at its lower end, a gear, K, which is adapted to be actuated by suitable mechanism—similar, for instance, to that in the patents above referred to—for the purpose of communicating motion to the machine.

In Fig. 4 one pair of the switch-levers B C is removed to show the holes d d in the platform A, which form bearings for the studs e e, by means of which the switch-levers are pivoted on the platform.

The arrangement of coiled springs b c, encircling the shafts of the switch-levers for the purpose of returning them to their normal positions after the passage of the travelers, as seen in Figs. 2 and 5, may be varied, if desired, and I do not therefore confine myself to this particular construction, as it is obvious that the switch-levers may be operated by spiral or flat springs placed above the platform A, or arranged in any other suitable manner. The base of each traveler is composed of two

disks, *l* *q*, a cylindrical neck, *r*, and a projecting foot, *t*, as seen in Figs. 6 and 7. In practice the upper disk of the traveler-base carries the spool-frame, and there is placed above the whole machine a suitable take-off mechanism for taking up the finished cord and winding it up or conveying it away; but these devices are not shown, as they form no part of my invention, and may be, for instance, similar to those in the patents above referred to.

The machine here represented contains fifteen travelers, each carrier-gear *G* having five spaces, *g*, between its teeth for the reception of the necks of the travelers; but these carrier-gears *G* may be provided with any uneven number of these spaces *g*, and the number of travelers varied accordingly. The carrier-gears *G* are here shown as operated by engagement with the toothed ring *F*; but, if preferred, they may be rotated in any other suitable manner.

It is obvious that for varying or removing the twist of the cord, or in making a flat web, it may be desirable to revolve the guide-ring *F* in a direction either the same or opposite to that of the platform *A*; or the platform *A* may be made stationary and the guide-ring *F* revolved; but neither of these arrangements would disturb or change the relative positions of the carrier-gears *G* and travelers with respect to the guide-ring, and would not therefore interfere with the application of my invention thereto.

What I claim as my invention, and desire to secure by Letters Patent, is—

1. The combination, with the revolving platform *A*, having a circular recess or guide-path, *E*, of a traveler carrier-gear, *G*, applied

thereto, and a switch lever and spring for the purpose of automatically guiding the travelers alternately into and out of the recess or guide-path *E*, substantially as set forth.

2. The combination, with the revolving platform *A*, having a circular recess or guide-path, *E*, and a traveler carrier-gear, *G*, applied thereto, of the springs *b* *c* and the switch-levers *B* *C*, arranged upon opposite sides of the entrance to the recess or guide-path *E*, to operate reversely for the purpose of automatically guiding the travelers alternately into and out of the said recess or guide-path, whereby the machine is adapted to be run in either direction without adjustment, substantially as described.

3. The combination, with the revolving platform *A*, having a series of circular recesses or guide-paths, *E*, of the traveler carrier-gears *G*, applied thereto, and a series of switch-levers and operating-springs for the purpose of automatically guiding the travelers alternately into and out of the recesses or guide-paths *E*, substantially as set forth.

4. The combination, with the rotating platform *A*, with its circular recess or guide-path *E*, and switch lever or levers and spring or springs, of the stops *m* *n*, adapted to limit the range of motion of the switch lever or levers in opposite directions, substantially in the manner and for the purpose set forth.

Witness my hand this 8th day of November, A. D. 1882.

JAMES P. TOLMAN.

In presence of—

P. E. TESCHEMACHER,
W. J. CAMBRIDGE.
